UNITED STATES PATENT OFFICE

96,598

DESIGN FOR A LACE FABRIC OR SIMILAR ARTICLE

Eugenio Filippi, Fairview, N. J.

Application July 6, 1935, Serial No. 57,539

Term of patent 3½ years

To all whom it may concern:

Be it known that I, Eugenio Filippi, a citizen of the United States, residing at Fairview, Bergen County, State of New Jersey, whose post office address is 366 Delano Place, Fairview, New Jersey, have invented a new, original, and ornamental Design for a Lace Fabric or Similar Article, of which the following is a specification, reference being had to the accompanying drawing, forming a part thereof.

The figure is a plan view of the lace fabric showing my new design.

The design is an open work embroidered fabric. The hatched portions represent substantially solid material.

I claim:

The ornamental design for a lace fabric or similar article, as shown and described.

In testimony whereof I have signed this specification.

EUGENIO FILIPPI.
